UNITED STATES PATENT OFFICE.

FRANCIS M. CASE, OF CLEVELAND, OHIO.

CLEANER.

1,094,877.

Specification of Letters Patent. Patented Apr. 28, 1914.

Application filed September 26, 1910. Serial No. 583,866.

To all whom it may concern:

Be it known that I, FRANCIS M. CASE, a citizen of the United States, residing at Cleveland, in the county of Cuyahoga and 5 State of Ohio, have invented certain new and useful Improvements in Cleaners, of which the following is a specification.

This invention relates broadly to devices known as suction sweepers or cleaners, and 10 is particularly designed as an improvement over the construction set forth in my co-pending application filed of even date here-with.

The present invention relates particularly to an adjustable hood carrying the brush and arranged in a manner such that it may be raised or lowered freely to and from the surface operated upon without adjusting the forward rollers of the device, 15 thus rendering the machine easily adjustable in point of the distance of the mouth of the hood from the surface operated upon.

The invention also resides in certain details of construction hereinafter set forth 20 in the following description, drawings and claims.

Referring to the drawings, Figure 1 is a side elevation of the device, showing the carpet or fabric as it is drawn up from the 25 floor; Fig. 2 is a longitudinal vertical section; Fig. 3 is a section upon the line 3—3 of Fig. 2; Fig. 4 is a bottom plan view; Fig. 5 is a view showing the manner of holding the end of the discharge receptacle 30 or bag; Fig. 6 is a sectional view of one of the castors showing the handle journaled on the castor socket; Fig. 7 is a front elevation of the raising device secured to the hood and to the casing but with the nut and 35 clamping plate removed; Fig. 8 is a top plan view of the guiding member secured to the casing; Fig. 9 is a bottom plan view of the clamping plate; and Fig. 10 is a side elevation of the clamping screw and clamp- 40 ing plate.

In carrying out the invention any preferred form and construction of parts may be employed so long as they possess the necessary characteristics, but I have shown 45 one form in the drawings which is highly effective in operation, and in such embodiment the device comprises a main casing 1 in the form of a fan or blower scroll, and this casing has at the rear thereof a neck 50 portion 2 connected with an enlarged discharge member 3. The casing 1 is further

provided with an opening 4 with a finished surface 5 about the same for receiving the supporting ring 6 in the upper part of which is mounted the motor 7. The ring 6 is provided with a downwardly projecting flange 8 which is adapted to pass through the opening 4 and to extend flush with and preferably slightly beyond the upper inner surface of the casing, as shown in Fig. 2, and 55 for a purpose which will be described later. The motor 7 is provided with a vertically disposed shaft 9 having secured to it by a set screw 9' the hub 10 of a fan disk 11 provided with suitable blades 12 on its under- 60 side. The fan disk is constructed and arranged in a manner such that when it is in place the edge of the disk 11 is close to the lower edge of the flange 8, while the periphery of the disk extends to a point corresponding substantially with the outer periphery of the flange 8. The object of this arrangement is to cause the air above the disk to be discharged into the fan casing or scroll, so that the lodging of dirt above 65 the disk is prevented. The motor shaft 9 is further provided with a driving pulley 13 for a purpose to be described. The shaft 9, the hub 10 and the pulley 13 extend below the bottom of the main casing and through 70 an opening 14 therein.

The main casing at the rear is supported upon two castors 15—15, each of which is provided with a shank 16 extending up into a suitable socket member 17 secured to the 75 side of the casing and having an upwardly extending trunnion member 18 provided with a laterally extending pin 19 for engagement in an opening 19' in the corresponding end of a forked handle member 20 which is 80 provided with a socket 21 for receiving a handle 22. The socket member 21 is provided with a pair of ears 23 for receiving a link 24 swiveled in the end of a link 25 provided with a seat 26 for receiving the ears 23 when 85 the handle is in its lower position. The link 25 is pivoted upon a pin 25' mounted in ears 27 secured to the discharge member 3 of the casing. The forward end of the main casing is supported upon rubber-tired wheels 90 or rollers 28 mounted upon pins 29 each secured in the sides of a housing 30 forming a part of the main casing 1. These wheels or rollers support the casing of the device and hold it in a fixed position with respect 95 to the floor at all times.

The operation of the motor causes the ro-

tation of the fan and results in a suction being created through the opening 14 and a discharge through the discharge member 3, and in this instance the suction is utilized 5 in conjunction with a brush for bringing about the cleaning operation, and this mechanism will now be described, the device for receiving the discharge being described later.

10 Secured to a flange 31, which is integral with the lower portion of the main casing and is substantially U-shaped in form, is an inlet housing 32 which conforms to the configuration of the flange and is provided 15 with an opening 33 in its bottom which is adapted to be closed by a plate 34 held in place by means of a latch spring 35 which engages above the bottom inner surface of the inlet housing after having been first 20 passed through notches or openings 36 in the bottom of the inlet housing, as shown in Fig. 4. The latch spring 35 is manipulated by a knurled finger piece 35' having a portion extending through an opening in 25 the cover plate and secured in the spring. The housing is still further provided with an opening 37, as shown in Fig. 3, in its forward end, and the lower edge of the bottom of the inlet housing at this opening is 30 curved at 38 for receiving a corresponding curved portion 39 of a suction hood shank 40 which tapers outward in a lateral direction from the inlet housing and forms a part of a suction hood 41 which is arranged be- 35 yond the front edge of the main casing 1. This housing is pivoted so as to swing up and down at its outer end, and this pivot is formed by suitable screws 42 which pass loosely through the sides of the inlet hous- 40 ing and into bosses 42' in the side walls of the hood shank.

45 The suction hood 41 is provided with a substantially rectangular opening or mouth 43 in the bottom thereof, as shown in Fig. 4, and the edge of the casing about this opening is enlarged to form flat surfaces 44. At each end the hood is provided with a vertically disposed slot 45 which receives a slide or block 46. Each of these blocks 46 50 is provided with a flange 47 extending over onto the end of the suction hood and with a vertically disposed slot 48 for receiving a brush shaft 49. This shaft is held in place at the ends of the hood by means of suitable 55 nuts 50 upon the ends of the shaft. Mounted on the shaft 49 is a rotary brush 51 pro- 60 vided at one side of its center with a pulley 52 which is adapted to be driven by a belt 53 from the pulley 13. The movement of the hood upon its pivot is for the purpose of adjusting the mouth of the hood to and from the surface to be operated upon, as for example, in case of sweeping floors the hood is dropped close to the floor, while in sweep- 65 ing or cleaning carpets the hood is raised

so that the suction created by the fan will raise the carpet from the floor against the mouth of the hood where it will be operated upon by the brush.

In order to hold the hood in any adjusted 70 position suitable mechanism is provided, and it comprises a guide member 54 secured to the forward end of the main casing 1 and having a pair of upwardly extending flanges 55 which receive between them an 75 arc-shaped adjusting segment 56 which is preferably integral with a base portion 57 secured to the hood. A suitable finger piece 58 is also arranged integral with this base 57 and serves as a means for manually 80 raising the hood, the segment 56 sliding between the flanges 55 of the guiding member 54. The convex upper surface of the segment 56 is provided with serrations or trans- 85 verse teeth 59 which coöperate with a ser- rated block 60 which is provided with an opening 61 for the passage of the shank 62 of a thumb screw 63 which is threaded into the guiding member 54. By this arrange- 90 ment of serrated segment and block the hood may be held in any desired position relative to the floor.

The discharge member 3 is provided with an annular flange 64 and with diametri- 95 cally opposed ears 65, the latter having suit- able clamping screws 66 pivoted therein. Each of these clamping screws is provided with a clamping nut 67. The annular flange 64 is arranged at a slight distance from the outer edge of the discharge mem- 100 ber so that the latter may receive a ring 68 of a dirt-catching receptacle or bag 69 which is secured upon this ring at its edge so that a mouth is formed corresponding in size to the exterior of the discharge member 105 3. This ring 68 at the mouth of the dis- charge receptacle is held in place by a clamping ring 70 which is provided with dia- 110 metrically disposed slotted projections 70'. The slots in these projections receive the clamping screws 66, and when the clamping nuts 67 are drawn up tightly, the discharge receptacle is firmly held in place with the opening therein in communication with the opening in the discharge. The 115 rear end of the discharge receptacle, which is in this instance a sack, is supported by a loop 71 which is passed over the handle be- 120 fore the receptacle is secured in place.

In operation the user adjusts the hood so 120 that its mouth is at the proper distance from the surface to be operated upon and the motor is started, when atmospheric air will be drawn in at the mouth of the hood and discharge into the receptacle 69, all the dust and dirt being drawn from the surface treated and being conveyed with the air into the receptacle. Since the receptacle is made of a fabric, the air passes through and the dust and dirt is collected within the 130

same from whence it may be discharged in any suitable manner.

5 A suitable guard is provided for the brush and it comprises a bar 72 arranged near the forward end of the suction hood on the inside and at the inlet opening and having secured in it suitable fingers 73 extending across the inlet opening or mouth thereby preventing the surface-covering from being 10 drawn into the suction hood.

Having described my invention, I claim:—

1. In a cleaner for surface coverings, a main casing, supporting means therefor, a suction hood pivoted to the casing and in 15 open communication therewith and projecting freely beyond all supporting means for the entire device, said suction hood being provided with a mouth having its edges in a single plane substantially in parallelism 20 with the surface covered and at a distance therefrom greater than the thickness of the surface covering, means for adjusting the said hood for coverings of different thicknesses, means within the hood for vibrating 25 the surface covering operated upon, and means for creating a suction within the casing and within said hood sufficient to suspend the surface covering against said mouth.
- 30 2. In a cleaner, a main casing, supporting wheels therefor, a housing carried by said casing and in open communication therewith, said housing having an inlet opening, a suction hood pivoted in the inlet opening 35 in said housing and in open communication therewith, said hood having a mouth, means for holding said suction hood in any adjusted position, a brush mounted in said hood above the mouth therein, means for creating 40 a suction in the main casing and the suction hood, and means for rotating the brush.
3. In a cleaner, a main casing, supporting wheels therefor, a housing secured to the underside of said casing and in open 45 communication therewith and provided with an inlet opening in its side, a suction hood having a mouth and a hollow shank pivoted in the inlet opening of said housing, said

shank establishing communication between the suction hood and the housing, a brush 50 rotatably mounted in said hood above the mouth, means for creating a suction within the casing and within the hood, means for rotating said brush, and means for holding the hood in any adjusted position. 55

4. In a cleaner, a main casing, supporting wheels therefor, a housing secured to the underside of said casing and in open communication therewith and provided with an opening in its side, a suction hood having 60 a mouth and a hollow shank pivoted in said side opening of the housing, said shank establishing communication between the suction hood and the housing, a brush rotatably mounted in said hood above the mouth therein, means for creating a suction 65 within the casing and within the hood, means for rotating said brush, an arc-shaped arm carried by said hood and provided with serrations, a guide for said arm carried by 70 the main casing, a serrated block adapted to engage the serrations of said arm, and suitable clamping means provided between the block and the guide for holding the serrated parts in engagement. 75

5. In a cleaner, a main casing provided with a discharge opening and an inlet opening in its bottom, a housing secured to the casing about said inlet opening, said housing being provided with an opening in its 80 side, a suction hood having a hollow shank extending into the opening in said housing and pivotally mounted therein, pivot pins connecting the housing and said shank, a brush mounted in said suction hood, means 85 for holding the suction hood in any adjusted position, means for creating a suction within the main casing and within the suction hood, and means for rotating said brush. 90

In testimony whereof I affix my signature in presence of two witnesses as follows.

FRANCIS M. CASE.
